UNITED STATES PATENT OFFICE

138,320

DESIGN FOR AN AUTOMOBILE ACCELERATOR PEDAL ATTACHMENT

Spurgeon L. Johnston, Tiburon, Calif.

Application March 29, 1944, Serial No. 113,061

Term of patent 14 years

(Cl. D14—6)

To all whom it may concern:

Be it known that I, Spurgeon L. Johnston, a citizen of the United States, residing at Tiburon, in the county of Marin and State of California, have invented a new, original, and ornamental Design for an Automobile Accelerator Pedal Attachment, of which the following is a specification, reference being had to the accompanying drawing, forming part thereof.

Figure 1 is a side elevational view of an auto-

mobile accelerator pedal attachment, showing my new design,

Figure 2 is an elevational view of the opposite side,

Figure 3 is a front elevational view, and

Figure 4 is a top plan view thereof.

I claim:

The ornamental design for an automobile accelerator pedal attachment, as shown.

SPURGEON L. JOHNSTON.
